CARTON

William H. Inman, Newark, N. Y., assignor to
 Bloomer Bros. Company, Newark, N. Y., a corporation of New York

Application August 20, 1942, Serial No. 455,408

14 Claims. (Cl. 229—16)

This invention relates to cartons made of cardboard or other foldable material cut, scored and folded to form a container for articles of food materials, fragile articles or the like, one object being to provide a carton of the above character having multiple wall thicknesses and improved strength and insulating qualities.

Another object is the provision of such a carton made from a single blank of material cut, scored and folded to form walls of multiple plies of the blank material arranged to afford more complete sealing of the carton against surrounding atmosphere.

A further object is to provide a carton of the character described in advantageous combination with one or more separately formed sheets of special insulating materials for completing the sealing of the carton and the protection of food materials or other contents from light rays, gases, moisture and other external conditions.

To these and other ends the invention resides in certain improvements and combinations of parts, all as will be hereinafter more fully described, the novel features being pointed out in the claims at the end of the specification.

In the drawings:

Fig. 1 is a plan view of a blank cut and scored for folding to make the carton;

Fig. 2 is a view showing the left hand half of the blank reversely folded to overlap the right hand half;

Fig. 3 is a fragmentary view showing the left hand section of Fig. 2 folded toward the right;

Fig. 4 is a similar view with the right hand section partially shown in Fig. 3 folded toward the left to complete the carton in collapsed condition;

Fig. 5 is a sectional view on the line 5a—5a in Fig. 2;

Fig. 6 is a sectional view on the line 6a—6a in Fig. 3;

Fig. 7 is a sectional view on the line 7a—7a in Fig. 4;

Fig. 8 is a perspective view showing the carton erected with the closure flaps at one end unfolded;

Fig. 9 is a similar view, partly broken away, showing the end closure flaps partially folded;

Fig. 10 shows a transverse section through the carton between its ends;

Fig. 11 is a sectional view, partly broken away, on the line 11a—11a in Fig. 13;

Fig. 12 is a similar view on the line 12a—12a in Fig. 13;

Fig. 13 is a perspective view, partly broken

away, showing the end closure flaps completely folded;

Fig. 14 is a plan view of the cardboard blank shown in Fig. 1, but having associated therewith two separately formed liner sheets;

Fig. 15 is a view similar to Fig. 7 but including the liners shown in Fig. 14;

Fig. 16 is a perspective view similar to Fig. 8 but including the said liners, and

Fig. 17 is a similar view showing each of the liners, and all of the end flaps but one, folded down to close the carton.

In the preferred embodiment of the invention, herein disclosed by way of illustration, the carton is formed principally from a one-piece blank of cardboard, cut and scored for folding and comprising a series of side wall sections, 1 to 8, inclusive, arranged in contiguous side by side relation, as shown in Fig. 1. Sections 1 to 4, inclusive, which form the set of inner side walls, as hereafter described, are of slightly less width than the sections 8 to 5, respectively, which form the set of outer side walls. Section 1 is extended to provide an attaching strip 9 separated by a scored folding line 10. Section 8 is extended to provide an attaching strip 11 separated by a scored folding line 12.

Certain of side wall sections 1 to 8 carry extensions forming flaps for closing the ends of the carton, which latter are the same, so that a description of the flaps at one end will suffice for both. Section 1 carries a flap 13, preferably of the same size as the interior cross section of the carton, separated by a scored folding line 14 and being otherwise unattached. Section 2 carries an extension 15, also preferably of the same size as the interior of the carton, separated from the blank by a scored folding line 16, but being otherwise unattached. Flap 15 carries a securing tab 17 separated from it by a scored folding line 18. Section 3 carries a flap 19 similar to the flap 13. Section 4 carries a flap 20 similar to the flap 15, with a tab extension 21 similar to the tab 17, except that the tab 17 is preferably tapered at its sides, as indicated at 22.

At the opposite end of the blank, section 8 carries a closure flap extension at each end, as at 23, separated by a scored folding line 24. Flap 23 has at its outer end a tab 25 separated by a scored folding line 26. On each side of flap 23 is a tab, as 27, separated by a scored folding line 28 and being otherwise unattached.

The side walls 1 to 8 are marked off or separated from each other by scored folding lines, as

shown at 28, about which they are folded at right angles to one another to form the sides of the carton. The folding line 30 between sections 4 and 5, however, is scored more deeply than the others, preferably comprising intermittent cuts 31 extending entirely through the material, to insure precise folding along this line at the center of the blank as one half of it is bent to overlap the other, as hereafter described.

In folding, the blank is reversely folded upon itself adjacent its center, by folding the left hand half, as shown in Fig. 1, about the central score line 30, so that it overlaps and lies against the right hand half of the blank, as shown in Fig. 2. Section 1 is then folded to the left about the intermediate score line to lie against section 2, as shown in Figs. 3 and 6, and sections 4 and 5 together are then folded toward the right over section 3 and over the securing strip 9 of section 1, as also shown in Figs. 3 and 6. Section 8 is then folded toward the left to overlie section 1, as shown in Figs. 4 and 7, with its securing strip 11 overlying section 5. Securing strips 9 and 11 are preferably coated with adhesive so that when so folded, they are adhesively secured to sections 4 and 5 respectively. In the completed form shown in Figs. 4 and 7, the carton is collapsed in a compact, flat condition conveniently adapted for storage, packaging, or transportation in quantities.

In erecting the carton from the collapsed condition of Figs. 4 and 7, the side walls are swung into right angular relation with one another in the tubular form shown in Figs. 8 to 13, inclusive, with the inner and outer sets of side walls affording a double walled construction. The reversely folded central portion of the blank at the folding line 30, Fig. 10, is shown located at a corner fold between adjacent carton sides and there inserted between the overlapping opposite ends, or gummed securing strips 9 and 11. In this condition the carton is ready for filling and closing by the folding and securing of the end flaps.

The end flaps are the same, in the present instance, at each end of the carton, so that a description of those at one end will apply to both. Referring to Fig. 8, it will be seen that the flaps 13 and 19 extend at opposite sides of the carton and these flaps are preferably first folded down, in overlapping relation with each other, to close the carton, as indicated in Fig. 9. Thereafter, the opposite flaps 15 and 20 are folded down over the flaps 13 and 19 and their end tabs, 17 and 21, are folded and tucked in between the separate inner and outer side walls, as indicated in Fig. 9, thereby securing these flaps in closed condition. To still more tightly seal the end closure, flap 23 is then folded down and its tabs 25 and 27 are likewise securely tucked in between the separate double side walls, all as shown in Figs. 11 to 13, inclusive. The closed ends of the carton may then be dipped in paraffin or other known or suitable liquid for coating and further sealing the same.

It will be apparent from the above description that the blank is shaped to be readily die cut of the sheet material and cut and scored for folding by known means and methods. The substantial scoring of the central fold line 30, as by means of the through cuts 31, insures precise folding along this line and accurate alignment of the folded halves of the blank with each other, as shown in Fig. 2, which is of particular importance in the case of relatively long folded portions of material, as in the present instance.

Although such deep scoring at the fold line 30 might otherwise tend to leakage, it will be noted that this fold line is substantially overlapped and strengthened and sealed by the securing strips 9 and 11 between which it is inserted and adhesively secured, so as to counteract any such tendency to leakage.

The construction has the further advantage that the inner and outer walls of each side of the carton are separate from each other throughout substantially the whole width of each side adjacent the ends thereof and preferably from end to end, so that the two walls of each side may move slightly relatively to each other and 10 may be spaced for the insertion and securing therebetween of the tabs of the end flaps. Moreover, with the inner side walls of slightly less width than the outer side walls, this construction enables the blank to be folded and adhesively 15 secured, as shown in Figs. 4 and 7, with entire facility, the double walls being free to easily fold and slide slightly on each other, without distorting or otherwise interfering with the proper shape, accurate folding and desired relation of 20 the parts, the inner and outer sets of side walls being connected with each other only by a single thickness of the blank material extending integrally from one of said sets to the other at the fold line 30 in one of the corners between 25 30 adjacent side walls.

The double wall construction affords the further advantage of an ample number of end closure flaps which may be located on both sets of side walls. Thus, in the present instance, 30 flaps 13, 15, 19 and 20 are located on the inner set of side walls, while flap 23 and its tabs 25 and 27 are located on the outer set, supplying in this case five thicknesses of material closing the ends of the carton and secured in place by 35 five tabs tucked into the spaces between the side walls. A further meritorious feature lies in the adaptability of the cardboard structure described above to combination with separately formed walls of one or more special insulating materials.

Such additional insulating walls are preferably 40 provided by one or more separately formed sheets of insulating material associated with the cardboard blank described above. Thus Fig. 14 shows the said cardboard blank having applied thereto 45 a separately formed sheet of foldable material 32 of substantially rectangular shape, which is applied in the present instance over the side walls 5, 6, 7 and 8 so as to be interposed and enclosed between the two halves of the blank when folded as above described. The end of blank 32 overlying 50 section 8 of the main blank is preferably extended as at 33 to partially overlap securing strip 11. After the blank is folded as above described to form the carton, the insulating liner 32 is folded with it as shown in Fig. 15, being held between and protected by the inner and outer side walls. Blank 32 has ends which extend as far as the ends of the closure flaps, as shown in Fig. 16, and these extended end portions of blank 32 are folded inwardly from each side in overlapping folds 34, to further close the ends of the carton and completely cover the contents, as indicated in Fig. 17, these folds being finally covered by the outer end flap 23.

In addition to the liner interposed between the double walls of the carton, as above described, an additional liner of insulating material may be employed and arranged to cover the inner surfaces of the inner walls. Such a liner is shown, 70 for example, at 35, Fig. 14, of rectangular shape,

and preferably secured to and mainly overlying sections 1, 2, 3 and 4 on the sides thereof which become the inner surfaces of the carton. Liner 35, at one of its ends, 36, is preferably spaced inwardly from the edge of section 4 of the main blank, so as not to interfere with the adhesive attachment of section 4 to strip 9 of section 1. The other edge 37 of the liner, however, is preferably extended somewhat beyond the securing strip 9 of section 1 of the main blank, so as to overlie edge 36 for adhesive attachment thereto. Liner 35 extends at its ends substantially as far as the end closure flaps, and these end extensions of the liner provide material which is folded across the ends of the carton under the end flaps 13 and 19, so as to completely enclose the contents of the carton.

The above described liners may be made of any material suitable for accomplishing the types of insulation desired. Thus, I prefer to make the intermediate liner 32, which is protected between the inner and outer walls, of light-insulating, substantially opaque material for protecting the contents of the carton when employed to contain materials, such as certain foods, which are sensitive to injury by light. A material which I have found satisfactory for the purpose, for example, is the substantially black paper which is commercially available and commonly employed for wrapping sensitive photographic plates and film, to protect the same from light. This intermediate liner 32 may have water resistant qualities, but I preferably employ for that purpose the inner liner 35 which is in contact with the contents of the carton. Liner 35, for example, may be made of Cellophane, or any known and suitable moisture vapor resistant material.

The above described construction of the main cardboard portion of the carton, with its separate inner and outer walls, is peculiarly adapted and advantageous for use with an intermediate liner such as described, since the spacing of the inner and outer walls may be readily made sufficient to accommodate the inserted thickness of the liner.

The cardboard blank is made of a weight and quality of cardboard, as well understood in the art, suited to the thickness and purposes desired, but I preferably employ cardboard insulated on both sides by cold water waxing, using, preferably, a mixture of equal proportions of micro-crystalline wax and regular paraffin wax, as well understood in the art. In the case of any of the above modifications, I may further complete the sealing of the closed carton by dipping each end and adjacent side wall portions in molten wax, such as described above which, upon cooling, forms a continuous coating which seals the joints between the enclosure flaps and side walls, as indicated at 38 in Figs. 11 to 13 inclusive.

The described construction affords, in effect, a pair of complete, inner and outer cartons, the inner and outer surfaces of each carton being preferably waxed as described, so that the main blank alone provides the protection of at least four waxed surfaces which may be increased, where desired, by the addition of one or two liners of insulating material especially adapted to the particular contents of the material, or the external conditions to which the carton may be subjected. The coating of the carton ends, after closing, adds still further protection, and these various provisions may be employed to supply a carton which is highly resistant to light rays, temperature variations, moisture vapor, gases, insects and the like. These qualities are particularly useful in the packaging, shipment and

preservation of foods such, for example, as dried meat, dehydrated vegetables and the like, in which a low moisture content must be maintained to prevent deterioration in flavor, taste and appearance, as well as freedom from bacteria.

It will thus be seen that the invention accomplishes its objects, and while I have herein described the details of one preferred embodiment of the invention, it is to be understood that such description is intended in an illustrative, rather than a limiting sense, as it is contemplated that various changes in the construction and arrangement of the parts will readily occur to those skilled in the art within the spirit of the invention as defined in the appended claims.

I claim:

1. A carton made of foldable waxed fibrous sheet material and comprising a blank reversely folded upon itself adjacent its center and having said folded center adhesively secured and sealed to its opposite ends to provide inner and outer sets of carton side walls, the inner and outer walls of each carton side being separate from each other throughout substantially the whole width of said side adjacent the ends thereof, extensions on the walls of said sides forming end closure flaps, tabs on said flaps inserted and held between said separate inner and outer walls of said carton sides and moisture resistant material adhesively sealing said closure flaps to said side walls.

2. A carton made of foldable waxed fibrous sheet material and comprising a blank reversely folded upon itself adjacent its center to provide inner and outer sets of carton side walls, said fold being located at a corner fold between adjacent carton sides and being there inserted and adhesively secured and sealed between the overlapping opposite ends of said blank, extensions on the walls of certain of said sides forming end closure flaps, tabs on certain of said flaps inserted and held between the inner and outer walls of said carton sides and moisture resistant means for sealing said end closure flaps and side walls.

3. A carton made of foldable waxed fibrous sheet material and comprising a blank reversely folded upon itself adjacent its center to form inner and outer sets of carton side walls, said sets being connected with each other only by a single thickness of said material extending integrally from one of said sets to the other at a corner fold between adjacent carton sides and by adhesive attachment of said folded center to the opposite ends of said blank, extensions on the walls of said sets forming end closure flaps for the carton, tabs on said flaps inserted and held between said inner and outer walls of said carton sides and moisture resistant means for sealing said end closure flaps and side walls.

4. A carton made of foldable waxed fibrous sheet material and comprising a blank reversely folded upon itself adjacent its center to provide overlapping sets of inner and outer carton side walls, said material being substantially scored along said fold to control the folding of said sets in accurate alinement with each other and said fold being located at a corner fold between adjacent carton sides and there inserted and adhesively secured between the overlapping opposite ends of said blank, the inner walls of said carton sides being of slightly less width than the corresponding outer walls, respectively, and said inner and outer walls of said carton sides being separate from each other, extensions on the

walls of certain of said sides forming end closure flaps, tabs on certain of said flaps inserted and held between the inner and outer walls of certain of said carton sides and moisture resistant material adhesively sealing said closure flaps to said side walls.

5. A carton made of foldable waxed fibrous sheet material and comprising a blank reversely folded upon itself adjacent its center to form inner and outer sets of carton side walls, said sets being connected with each other only by a single thickness of said material extending integrally from one of said sets to the other at a corner fold between adjacent carton sides and by adhesive attachment of said folded center to the opposite ends of said blank, said inner walls being of slightly less width than the corresponding outer walls, respectively, and said inner and outer walls being separate from each other, extensions on the walls of said sides forming end closure flaps, tabs on certain of said flaps inserted and held between said separate inner and outer walls of certain of said carton sides and moisture resistant material adhesively securing said closure flaps to said side walls.

6. A carton made of foldable waxed fibrous sheet material and comprising a one-piece blank reversely folded upon itself adjacent its center to provide overlapping inner and outer sets of carton side walls, the walls at the ends of said blank opposite said fold being extended to form attaching strips, said fold being located at a corner fold between adjacent carton sides and being there inserted and adhesively secured between said strips, the inner walls of said carton sides being of slightly less width than and separate from the corresponding outer walls, respectively, extensions on the walls of said sides forming end closure flaps, tabs on said flaps inserted and held between the inner and outer walls of said carton sides and moisture resistant means for sealing said end closure flaps and side walls.

7. A sealed carton for containing and preserving food substances, said carton being made of foldable waxed fibrous sheet material and comprising a blank reversely folded upon itself adjacent its center and having said folded center adhesively secured and sealed to its opposite ends to provide inner and outer sets of carton side walls, the inner and outer walls of each carton side being separate from each other, extensions on the walls of said sides forming end closure flaps, and tabs on said flaps inserted and held between said separate inner and outer carton side walls to hold said flaps in carton closing position, the joints between the said flaps and side walls being sealed by a continuous coating of water resistant material.

8. A sealed carton for containing and preserving food substances, said carton being made of foldable waxed fibrous sheet material and comprising a blank reversely folded upon itself adjacent its center to provide inner and outer sets of carton side walls, said fold being located at a corner fold between adjacent carton sides and being there inserted and adhesively secured between the overlapping opposite ends of said blank, extensions on the walls of certain of said sides forming end closure flaps, means for securing said flaps in closed position, and a coating of water resistant material sealing the joints between said flaps and said carton sides.

9. A sealed carton for containing and preserving food substances, said carton being made of foldable waxed fibrous sheet material and com-

prising a blank reversely folded upon itself adjacent its center to provide inner and outer sets of carton side walls, and having said folded center adhesively sealed to its opposite ends, the inner and outer walls of each carton side being separate from each other, a liner of insulating material enclosed between the inner and outer walls of each carton side, extensions on the walls of said sides forming end closure flaps, tabs on said flaps for engagement with said walls and moisture resistant means for sealing said end closure flaps and side walls.

10. A sealed carton for containing and preserving food substances, said carton being made of foldable waxed fibrous sheet material and comprising a blank reversely folded upon itself adjacent its center to provide inner and outer sets of carton side walls and having said folded center adhesively secured and sealed to its opposite ends, the inner and outer walls of each carton side being separate from each other, a light-insulating liner of substantially opaque material enclosed between the inner and outer walls of each carton side, extensions on the walls of said sides forming end closure flaps, tabs on said flaps for engagement with said walls and moisture resistant means for sealing said end closure flaps and side walls.

11. A sealed carton for containing and preserving food substances, said carton being made of foldable moisture resistant sheet material and comprising a one-piece blank reversely folded upon itself adjacent its center to provide aligned overlapping inner and outer sets of carton side walls, the walls at the ends of said blanks opposite said fold having extensions forming attaching strips, said fold being located at a corner fold between adjacent carton sides and being there inserted and adhesively secured between said strips, a liner of foldable insulating material interposed and supported between said sets of side walls and having extensions folded over the ends of said carton, extensions on the walls of said sides forming end closure flaps, tabs on said flaps inserted and held between said inner and outer side walls of said carton and moisture resistant means for sealing said end closure flaps and side walls.

12. A sealed carton for containing and preserving food substances, said carton being made of foldable moisture resistant sheet material and comprising a blank reversely folded upon itself adjacent its center to provide inner and outer sets of carton side walls and having said folded center adhesively secured to its opposite ends, the inner and outer walls of each carton side being separate from each other, extensions on the walls of said sides providing end closure flaps, said inner and outer walls and flaps forming, substantially, a pair of inner and outer cartons, a liner of insulating material interposed between said cartons, and a liner of insulating material covering the inner surfaces of the inner of said cartons.

13. A sealed carton for containing and preserving food substances, said carton being made of foldable waxed fibrous sheet material comprising a blank reversely folded upon itself adjacent its center to provide inner and outer sets of carton side walls, the walls at the ends of said blank opposite said fold having extensions forming attaching strips, said fold being located at a corner fold between adjacent carton sides, and being there inserted and adhesively secured between said strips, a liner of separately formed, foldable,

substantially opaque material interposed and supported between said sets of side walls, and having extensions folded over the ends of said carton, extensions on the carton side walls forming end closure flaps, tabs for securing the flaps in closed position, and a coating of moisture resistant material covering the outer surfaces of the ends of said carton and sealing the joints between said flaps and side walls.

14. A sealed carton for containing and preserving food substances, said carton being made of foldable waxed fibrous sheet material and comprising a one-piece blank reversely folded upon itself adjacent its center to provide aligned overlapping inner and outer sets of carton side walls, the walls at the ends of said blank opposite said

fold having extensions forming attaching strips, said fold being located at a corner fold between adjacent carton sides and being there inserted and adhesively secured between said strips, a liner of foldable insulating material interposed and supported between said sets of side walls and having extensions folded over the ends of said carton, a liner of foldable insulating material located inside said inner side walls and having extensions folded over the ends of said carton, extensions on the carton side walls forming end closure flaps, and tabs on said flaps inserted and held between said inner and outer carton side walls and holding the folded extensions of said liners and said flaps in carton closing position.

WILLIAM H. INMAN.
